CLAIM

The ornamental design for an insulated container, as shown and described.

DESCRIPTION

FIG. 1 is a front perspective view of the insulated container;

FIG. 2 is a front view thereof;

FIG. 3 is a rear view thereof;

FIG. 4 is left side view thereof;

FIG. 5 is a right side view thereof;

FIG. 6 is a top view thereof; and,

FIG. 7 is a bottom view thereof.

The evenly broken lines in the drawings depict unclaimed portions of the insulated container; the dash-dot broken lines disclose unclaimed boundaries of the claim; the broken lines form no part of the claimed design. The symbolic brake lines, shown in dash-dot lines, depict indeterminant length; the appearance of any portion between the symbolic brake lines forms no part of the claimed design.
